UNITED STATES PATENT OFFICE

2,038,991

SEALING DEVICE FOR REFRIGERATOR CABINETS

Irwin L. Wise, Chicago, Ill., assignor to Sealzit Corporation, Chicago, Ill., a corporation of Illinois

Application March 22, 1935, Serial No. 12,388

3 Claims. (Cl. 220—14)

This invention relates to sealing devices for refrigerating cabinets such as are commonly employed at soda fountains for dispensing purposes, such cabinets being adapted to contain one or more ice cream cans from which the ice cream is ladled.

The cans are customarily spaced from the surrounding walls of the cabinet and this space around the cans is, in the older type of cabinets, packed with ice and, in the newer type, accommodates the refrigerating coils by which the required low temperature of the cans is maintained. The removal of the cover of the cabinet, for the purpose of ladling the cream from the can, exposes the space around the can to the atmosphere with the result that circulation of air in this space is set up which not only diminishes the refrigerative efficiency of the cabinet but also promotes condensation and the collection of moisture in the space around the can.

One of the primary purposes of my present invention is to provide a sealing device which will seal the upper end of the space surrounding the can so as to prevent the undesirable air circulation therein, thereby increasing the efficiency of the cabinet and decreasing the objectionable condensation and moisture accumulation.

In accomplishing this result, my invention also aims to provide a device which will form an effective seal around the ice cream can itself and also an effective seal with the walls of the surrounding chamber, and in addition, it aims to provide a device which can be easily and quickly applied in position and as readily removed when occasion requires.

Other objects and advantages of my invention will be appreciated as the same becomes better understood by reference to the following description when considered in connection with the accompanying drawing.

Referring to the drawing:

Fig. 1 is a sectional view through an ice cream cabinet containing a plurality of ice cream cans and equipped with my invention;

Fig. 2 is a plan view of the construction shown in Fig. 1;

Fig. 3 is a plan view of my novel sealing device; and

Fig. 4 is a sectional view taken on the line 4—4 of Fig. 3.

Referring to the drawing more in detail, reference character 5 indicates generally the cabinet, 6 and 7 a plurality of cans set side by side therein, and 8 the opening in the top of the cabinet through which the ice cream cans are inserted

and removed and through which access to the cans is had for removal of their contents. This opening is customarily closed by a cover of any preferred construction, not shown.

My improved sealing device, indicated generally by reference character 9, is made preferably integrally of flexible elastic material such as cured rubber and is shaped to provide a plurality of openings 11 and 12 adapted to receive and snugly and sealingly embrace the upper ends of the pair 10 of ice cream cans.

From Fig. 4 it will be apparent that the walls 13 surrounding the openings are of substantial depth from top to bottom and that the walls of the openings taper outwardly from top to bottom 15 so as to facilitate the application of the sealing device to the cans. From Figs. 3 and 4 it will also be apparent that these surrounding walls substantially merge between the openings, as indicated at 14, and that at each side of this point of merger the space between the openings is covered by a connecting web 15 which is substantially thinner than the vertical depth of the peripheral walls.

Entirely around the perimeter of the device 25 there is formed a marginal flange 16 which extends upwardly and outwardly from the plane of the top of the openings, this flange being tapered from its base toward its outer edge, as best shown in Fig. 4, so that its perimeter is sufficiently flexible to conform to the walls of the chamber surrounding the can and effect a sealing contact therewith. The flange is also preferably made wider at one end of the device than at the other to accommodate it to the prevailing contour of 30 present day cabinets. To facilitate removal of the device from the cans it is provided preferably at one end with an integrally formed handle or finger grip 17.

In the use of my device, after the ice cream cans 40 have been placed in the cabinet, the sealing device is positioned by disposing it over the tops of the cans and pressing it down into a snug fit with the upper ends of the cans. The device 45 maintains the cans in position and in the case of paper cans, prevents their collapsing, forms a tight seal around each can, and also a tight seal with the surrounding walls of the chamber so that the chamber is effectively sealed against the atmosphere and circulation of air into and out of 50 the chamber is precluded while, at the same time, the dropping of particles of ice cream or other solid matter around the cans is prevented. When it becomes necessary to replace the cans, the device 55 may be readily removed by pulling upwardly

on the handle to detach it from the cans and the chamber.

In case the cabinet be constructed to receive single cans instead of doubles, the sealing device may be modified to comprise a single instead of a double opening, in which case the flexible marginal flange will be of uniform width entirely around the opening.

The details of construction in other particulars 10 may obviously be varied from those shown and described without departing from the spirit of the invention as defined in the following claims.

I claim:

1. A sealing device for refrigerating cabinet 15 comprising a body formed of flexible elastic material provided with a plurality of openings therethrough, each shaped and proportioned to snugly and sealingly embrace the outer surface of the upper portion of an ice cream can, said openings each being tapered outwardly from top to bottom, 20 said body being provided with a marginal tapered flange projecting outwardly and upwardly around the body and adapted to engage and conform to the walls of the surrounding chamber to provide 25 a seal for said chamber.

2. A sealing device for a refrigerating cabinet comprising a body formed of flexible elastic material provided with a plurality of openings shaped and proportioned to snugly and sealingly embrace the outer surface of the upper portion of an 5 ice cream can and provided with a tapered flexible flange extending at an angle to the plane of the body around the periphery thereof and adapted to engage and conform to the walls of the surrounding chamber so as to provide a seal for said 10 chamber.

3. A sealing device for a refrigerating cabinet comprising a body formed of flexible elastic material provided with an opening shaped and proportioned to snugly and sealingly embrace the 15 upper portion of an ice cream can, said opening being tapered outwardly from top to bottom, said device being provided at its upper edge with an outwardly and upwardly extending marginal 20 flange, said flange being tapered toward its outer edge and being sufficiently flexible to engage and conform to the walls of the surrounding chamber so as to provide a seal therefor.
